UNITED STATES PATENT OFFICE

VOLNEY WAYNE THOMSON, OF PORTSMOUTH, OHIO

DESIGN FOR AN ASH RECEIVER

Application filed November 9, 1929. Serial No. 33,393. Term of patent 14 years.

To all whom it may concern:

Be it known that I, VOLNEY WAYNE THOMSON, a citizen of the United States, residing at 1217 2nd Street, Portsmouth, Ohio, have invented a new, original, and ornamental Design for an Ash Receiver, of which the following is a specification, reference being had to the accompanying drawing, forming part thereof.

The single figure is a perspective view of the ash receiver, showing my new design.

I claim:

The ornamental design for an ash receiver substantially as shown.

VOLNEY WAYNE THOMSON.
